CLAIM

The ornamental design for a low cut sport shoe upper, as shown and described.

DESCRIPTION

FIG. 1 is a left side elevation of a low cut sport shoe upper of the present invention;

FIG. 2 is a right side elevation of the shoe;

FIG. 3 is a front elevation of the shoe;

FIG. 4 is a rear elevation of the shoe; and,

FIG. 5 is a top plan of the shoe.

The broken line showing of the bottom of the low cut sport shoe upper in the figures is for illustrative purposes only and forms no part of the claimed design.
